UNITED STATES PATENT OFFICE.

MAX SIMSON, OF NEW YORK, N. Y.

PROCESS OF MANUFACTURING RINGS.

Application filed January 29, 1923. Serial No. 615,708.

To all whom it may concern:

Be it known that I, MAX SIMSON, a citizen of the United States, residing at New York city, in the county of New York and State 5 of New York, have invented certain new and useful Improvements in Processes of Manufacturing Rings, of which the following is a specification.

This invention relates to the process or 10 method of manufacturing finger rings and has for its principal object the making of such rings by a novel series of operations of extreme simplicity and efficiency in their manufacture.

15 One of the objects of my invention is the process of manufacturing finger rings by stamping a blank to produce two complementary halves or sections which when combined, produce the shank and crown of 20 the ring wherein the gem setting may be placed.

Another object of my invention is the process of manufacturing finger rings wherein the shank and crown of two complementary 25 sections are stamped out of a blank in a single operation, said crown being so formed as to permit of its shaping to receive a polygonal or other design of gem setting as well as an ornamental insert as 30 may be desired.

In order to more fully understand the novel process and the steps by which the article of manufacture is produced, reference is had to the accompanying drawings 35 showing a preferred embodiment of my invention and wherein:

Figure 1 is a front view.

Figure 2 is a side view.

40 Figure 3 is a sectional view taken on the line 3—3 of Figure 2.

Figure 4 is a plan view with the plate or setting removed.

45 Figure 5 is a front view showing the blank before the insert and the plate or setting is mounted.

Figure 6 is a plan showing the blank preliminary to bending the respective sections toward each other to produce the shank and crown of the ring.

50 Figure 7 is an edge view in a partial plan of one of the sections of the blank showing the crown bent.

Figure 8 is a modified form showing the blank when joined at the sides.

55 Reference being had to Figures 1 and 6 of the drawings, a metal blank is first stamped

out or cut so as to form two connected shanks 5, 6, which are joined as indicated at 7. Each shank 5, 6, is formed integrally with its crown 8, 9, the outer edge of said 60 crown being partly cut away as indicated at 10, 11, for a purpose presently to appear. The crowns 8, 9, of the respective sections are bent along a line disposed centrally and vertically thereof as indicated at 12, 13, so 65 that the respective crowns may be bent outwardly as indicated at 14, 15, to form a seat or support for the gem plate or setting 16.

After the blank has been cut according to the shape and design as indicated by 70 Figure 6, the shanks 5, 6, are brought together by bending the same so that a burr or projection 16^a is formed on the outer end and at the bottom of the shank. The respective sections of the ring are soldered together so as to produce the single shank 17 above referred to and the burr 16^a may be 75 subsequently cut away or beaten out into the body of the shank of the ring as the same is worked and formed. The cut away 80 portions of the sides of the crown form a seat to receive the inserts 18, 19, which are soldered thereon preliminary to bending and forming the mounting to receive the 85 gem setting 16 above referred to.

When the respective sections are brought together they are left apart at the upper or crown portion of the ring and the said crowns 8, 9, are then bent outwardly from the shape as indicated by the dotted line 90 to the shape shown in full lines, see Figures 6 and 7, so as to receive the plate or gem setting. In this manner, a very accurate and precise fit can be had between the plate 16 and the inserts 18, 19, preliminary to 95 soldering the same and completing the formation of the ring. Consequently, various size settings may thus be placed on the crown. Of course both the inserts and the crown portions 8, 9, as well as the plate or 100 gem setting may be carved or otherwise designed preliminary to soldering the respective parts together to complete the manufacture of the article.

In the modified form, the same process 105 is carried out by a different die in cutting the original blank, it being observed that the shanks 5^a, 6^a, are joined at the side 7^a instead of at the bottom. The crowns however, of the respective sections are identical 110 with that described above and when the two sections are brought together, the burr

formed on the outer periphery of the shank adjacent the shoulder 9^a on which the inserts are placed, is of course cut away before the shank is completed. In this form of the invention, it will be noted that the crowns when formed after the first cutting operation are disposed closer to each other and consequently permit of further stamping or designing by means of a die or otherwise, 10 in but a single operation, however, the particular design or stamping of the crown or the inserts may be regarded as arbitrary depending upon the quality of the product to be manufactured but primarily my invention resides in the process of manufacturing 15 the article, according to the steps and in the manner above indicated.

While I have illustrated and described my invention, what I claim as new and desire 20 to secure by United States Letters Patent is:—

1. The process of manufacturing rings and ring findings which consists in cutting a blank to produce a pair of connected 25 shanks, bending said shanks toward each other and joining the opposing faces of the said shanks.

2. The process of manufacturing rings and ring findings which consists in cutting a blank to produce a pair of complementary 30 connected shanks, bending the crowns of the shanks outwardly, then bending the said shanks to produce a unit.

3. The process of manufacturing rings

and ring findings which consists in cutting 35 a blank to produce a pair of complementary connected shanks, bending the opposing crowns of the shanks outwardly, then bending the shanks toward each other so that the faces are disposed toward each other, 40 joining the opposing faces and removing the projection formed at the point of juncture between the two shanks.

4. The process of manufacturing rings and ring findings which consists in cutting 45 a blank to produce a pair of complementary connected shanks, each shank having a crown integral therewith, simultaneously bending the crowns outwardly along a line centrally 50 through the vertical axis of the shank, then bending the shanks toward each other, joining the opposing faces of the shanks and removing the projection formed at the point of juncture between the two shanks.

5. The process of manufacturing rings 55 and ring findings which consists in cutting a blank to produce a pair of complementary connected shanks with integral crowns, said crowns being partially cut away on their outer faces, bending the crowns outwardly 60 along a line medially of the sides, then bending the shanks toward each other, joining the opposing faces of the shanks, fitting a gem setting and inserts on the top and sides 65 of the crown respectively and joining said gem setting and inserts to the crown.

In testimony whereof I affix my signature.
MAX SIMSON. [L.S.]
